UNITED STATES PATENT OFFICE.

WILLIAM W. BEWSIC, OF ELYRIA, OHIO.

PRESSER-FOOT FOR SEWING-MACHINES.

No 839,708.

Specification of Letters Patent.

Patented Dec. 25, 1908.

Application filed April 27, 1904. Serial No. 205,109.

To all whom it may concern:

Be it known that I, WILLIAM W. BEWSIC, a citizen of the United States, residing at Elyria, in the county of Lorain and State of Ohio, have invented a certain new and useful Improvement in a Presser-Foot for Sewing-Machines, of which the following is a full, clear, and exact description, reference being had to the accompanying drawings.

10 In the manufacture of garments, generally and particularly underwaists, as set forth in my Patent No. 758,892, issued May 3, 1904, the buttons and the shoulder-straps, together with the tabs, are secured to the waistband by means of a strip which has its raw edges folded under and also has a row of stitching adjacent to each folded edge for the purpose of securing all the parts in place. When the buttons are secured by simply inserting 15 the tapes thereof under the edges of the strip and then stitching through the strip, through the tapes, and into the band, the buttons which are on the upper edge of the strip are liable to rip the stitching at that point and pull 20 out. It has therefore been found necessary to insert the tapes of the buttons under the strip and fold the tapes thereof back over and on top of the strip before it is stitched at this edge, so that the stitching will pass through 25 the tape, through the strip, through the tapes again, and then through the waistband. I have found that a great deal of time is saved in supplying a machine with a presser-foot which will permit the arrangement 30 of the tapes of the buttons in the manner just described, so that the parts may be all stitched at one operation, and this presser-foot is the subject-matter of my application.

While the invention may be applied to any 40 style of machine, I prefer to use it in connection with a double-needle machine and in connection with one of the type which is designed to sew a strip onto a band. In other words, I intend to provide a presser- 45 foot with a guide for the strip and with a passage-way running longitudinally through the foot between the two needles, whereby the buttons may pass therethrough and not in any way interfere with the operation of 50 the presser-foot or the needles.

The invention may be briefly summarized as consisting in the construction and combination of parts hereinafter described, and pointed out in the claims.

55 Referring to the drawings, Figure 1 is a perspective view showing the application of

a presser-foot to a double-needle machine. Fig. 2 is a top plan view, and Fig. 3 is a longitudinal vertical sectional view showing the guide-plate.

60 A represents the head of a double-needle machine, which is provided with the usual needle-bar A' and a presser-bar A''. The needle-bar A' has secured to it a cross-head a, carrying the two needles a' and a''. Secured to the presser-bar is the presser-foot B, which is substantially of the form shown and consists of the two foot portions b b', spaced apart to leave a passage therebetween. These two foot portions are arranged to coöperate with the ordinary throat-plate (not shown) and cause the feeding of the material to be sewed. These foot portions are also provided with needle-openings b².

75 Secured to the forward end of the foot portion b' is the strip-guide b³, extending up slightly in front of the foot, as shown, and provided at its forward end with a pair of downwardly-extending shoulders b⁴, to which is secured a rod b⁵, adapted to carry a guide-plate b⁶. The forward end of the foot portion b and the forward part of the foot portion b' are both arranged so that the passage between these foot portions b b' is continued 80 out at one side.

85 The operator passes the strip C through the guide formed by the rod b⁵ and plate b⁶ down into position under both of the presser-foot portions and on the upper side of the 90 waistband C'. The stitching operation is then begun. The buttons D upon the right side of the strip C have their tapes d inserted under the same, while those on the left-hand side are first inserted in between the foot portions and the tapes thereof drawn under the left-hand foot portion, then the free ends drawn back again against the edge of the guide-plate b⁶ and under the strip C. The feeding of the strip, together with the band, 95 causes the forward movement of the button-tapes, together with the buttons, which results in the sewing of all the parts in their proper relationship.

100 Having described my invention, I hereby claim—

1. In combination with a double-needle sewing-machine, a presser-foot therefor having a guideway between the needles, and a strip-guide in front of said guideway arranged to provide a feed-space between the strip-guide and the needles, said feed-space

- opening from the side and curving into said guideway, whereby a tape carrying a button may be fed from the side into the central guideway between the needles.
5. In combination with a double-needle sewing-machine, a presser-foot therefor having openings for the passage of the needles therethrough and a passage-way between said openings, said passage-way opening at one side of said presser-foot and in front of the needle-openings whereby buttons and their tapes may be fed in from the side and guided through the said passage-way between the needles, and a strip-guide carried by said foot and extending approximately from one side of the foot to the other across the front thereof, whereby the strip will be fed to both needles.
6. In combination with a double-needle sewing-machine, a presser-foot therefor consisting of two foot portions each having an opening therein for the passage of a needle therethrough, said portions being separated from each other to form a passage-way therebetween and said passage-way opening at the side of said foot and in front of the needle-openings whereby buttons and their tapes may be fed in from the side and directed between the needles, and a strip-guide secured to the forward end of one of said portions and extending substantially from one side of the foot to the other.
7. In combination with a double-needle sewing-machine, a presser-foot therefor consisting of two foot portions, one for each needle, said portions being separate from each other to form a passage-way therebetween, a strip-guide carried by one of said portions and extending substantially across to said other foot portion, and a guide-plate carried by said strip-guide below the same and extending under a portion of the passage-way.
5. In combination with a double-needle sewing-machine, a presser-foot therefor having two foot portions spaced apart to form a 45 passage-way therebetween, a strip-guide secured to one of said foot portions and extending across in front of the opposite foot portion and forming with that portion a side opening to said passage-way, a loop upon 50 said guide for the strip, and a plate secured to the lower portion of said loop extending down under the foot and under a portion of the passage-way.
6. In combination with a double-needle 55 sewing-machine, a presser-foot therefor having two foot portions spaced apart to form a passage-way for a button therebetween, a projection upon one of said foot portions which extends across in front of the other 60 foot portion, but allows for an entrance at the side of the foot to the passage-way between the foot portions, a loop carried upon the under side of said projection for guiding the strip to both needles, and a plate, carried 65 by one member of said loop, and extending down under the projection substantially across the opening at the entrance at the side thereof.
7. In combination with a double-needle 70 sewing-machine, a presser-foot having two foot portions, a guide carried by one of said portions for the strip, and a plate carried by said guide, said foot portions being spaced apart to form a passage-way for the button 75 and said plate extending under a portion of the passage-way thus formed.
- In testimony whereof I hereunto affix my signature in the presence of two witnesses.
